US00D841120S

(12) **United States Design Patent** (10) Patent No.: **US D841,120 S**
(45) Date of Patent: ** *Feb. 19, 2019

(54) **TOILET RIM-BLOCK**(71) Applicant: **S. C. Johnson & Son, Inc.**, Racine, WI (US)(72) Inventors: **Sara B. Schepp**, Caledonia, WI (US); **Meghan Marie McGuire**, Milwaukee, WI (US); **Steven A. Zach**, Waterford, WI (US)(73) Assignee: **S. C. Johnson & Son, Inc.**, Racine, WI (US)

(*) Notice: This patent is subject to a terminal disclaimer.

(**) Term: **15 Years**(21) Appl. No.: **29/592,594**(22) Filed: **Jan. 31, 2017**(51) LOC (11) Cl. **23-01**

(52) U.S. Cl.

USPC ..... **D23/208**(58) **Field of Classification Search**

Primary Examiner — Sheryl Lane*Assistant Examiner* — Calvin E Vasant(74) *Attorney, Agent, or Firm* — Banner & Witcoff, Ltd.(57) **CLAIM**

The ornamental design for a toilet rim-block, as shown and described.

DESCRIPTION

FIG. 1 is a top, front, right perspective view of a toilet rim-block showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
